U. 124

Des 129

James Waxe - Design for Stove -
Patented June 26th 1847.

Des. 129

James Wager, Troy, New York,
Letters Patent (Design No. 129 - dated 26 June 1844).

The schedule referred to in these Letters Patent and making
part of the same.

To all to whom these presents shall come, Be it known,
that I, James Wager, of Troy, in the County of Rensselaer,
and State of New York, have invented and produced a new design
for cooking stoves, and that the following is a full, clear, and exact
description thereof, reference being had to the accompanying drawings,
making part of this specification, in which figure 1 is an isometric
view of my stove castings; figure 2, an enlarged view of a por-
tion of the castings; and figure 3 a portion of the top plate.

The surface of my plates are plain with the except-
tion of the border which is a wreath of oak leaves inclosed in a border
on each side forming a broad border all around the side and
front and bottom plates; the top plate border is formed of leaves and
flowers as shown in figure 3. The corner ornaments are scroll formed.

The doors of my stove may be plain or ornamented with figures
as shown in figure 1; the front-plate has a projection the segments
of a circle in shape for the purpose of accommodating a large
boiler on the top of the stove.

I claim the above described and illustrated pat-
terns for stoves as my invention or production according to the act
in that case made and provided.

Witness,

N. V. W. Martin

John F. Learned.

James Wager
